N-DIALKYL ALKOXYNAPHTHAMIDINES

Richard Baltzly, New York, and Emil Lorz, Yonkers, N. Y., assignors to Burroughs Wellcome & Co. (U. S. A.) Inc., Tuckahoe, N. Y., a corporation of New York

No Drawing. Application November 16, 1948,
Serial No. 60,418

9 Claims. (Cl. 260—564)

1

The present invention relates to a new group of chemical compounds and more particularly to a new type of substituted amidines which have been found to possess outstanding properties as local anesthetics in veterinary medicine, especially for surface anesthesia. At least some of the new compounds are also believed to be suitable for application in human medicine, but at present the clinical tests on these compounds have not been completed.

The new compounds are readily prepared in excellent yield by the methods disclosed in our co-pending U. S. application Serial Number 700,366, of which the present application is a continuation in part.

The physiologically active compounds according to the present invention, may be graphically represented by the formula:

in which R and R' are alkyl groups containing together from four to ten carbon atoms, R'' is a lower alkyl group containing one to four carbon atoms.

As bases these amidines are only moderately stable and are insoluble or sparingly soluble in water. They are therefore best handled as their salts, which have very great stability and are readily soluble in water. The acid used to form the salts contributes nothing to the physiological activity of the substances and is not of a critical nature, provided it is not itself highly toxic. Hydrochloric acid, hydrobromic acid, sulfuric acid, phosphoric acid or organic acids such as malic acid, succinic acid, lactic acid or the like may be employed and any of these may offer advantages in individual cases but hitherto no other acid has been found preferable to hydrochloric acid. We therefore consider all non-toxic acids to be equivalent for this purpose and regard salts of this family of amidines with any such acid to be comprehended in the invention.

As an indication of the potency of these substances, when tested on the cornea of a guinea pig, 4-methoxy-N,N-di-n-butyl-alpha-naphthamidine is found to be 25 times as potent as cocaine while 4-methoxy-N,N-di-sec-butyl-alpha-naphthamidine is about 50 times as powerful. The toxicities, on the other hand, are only 2-3 times as great making the substances far more efficient and safe in application. When the size of the alkyl groups attached to the amidine nitrogen atom is increased the toxicity becomes greater and there is considerable local irritation, the di-

2

n-hexyl compound being unsuitable for use for that reason. Decrease in the size of these alkyl groups beyond a certain limit corresponds to a marked diminution in potency.

The following list of compounds, though not exhaustive, is believed to be representative of the physiologically active substituted amidines according to the present invention:

1. N - methyl - N - isopropyl - 4 - methoxy-alpha-naphthamidine.
2. N-methyl-N-n-butyl-4-methoxy-alpha-naphthamidine.
3. N-methyl-N-n-nonyl-4-methoxy-alpha-naphthamidine.
- 15 4. N-ethyl-N-n-octyl-4-methoxy-alpha-naphthamidine.
5. N,N - di-n-propyl-4-methoxy-alpha-naphthamidine.
6. N,N - di-isopropyl-4-methoxy-alpha-naphthamidine.
- 20 7. N - n - propyl - N - n - amyl-4-methoxy-alpha-naphthamidine.
8. N,N - di - n - butyl-4-methoxy-alpha-naphthamidine.
- 25 9. N,N - di - isobutyl-4-methoxy-alpha-naphthamidine.
10. N,N-di-sec-butyl-4-methoxy-alpha-naphthamidine.
11. N,N - di - n - amyl-4-methoxy-alpha-naphthamidine.
12. N,N - di-isoamyl-4-methoxy-alpha-naphthamidine.
13. N,N-diethyl-4-ethoxy-alpha-naphthamidine.
- 35 14. N-ethyl - N - n - propyl-4-ethoxy-alpha-naphthamidine.
15. N-ethyl-N-n-amyl-4-ethoxy-alpha-naphthamidine.
16. N-ethyl-N-isobutyl - 4 - ethoxy-alpha-naphthamidine.
- 40 17. N,N-di-n-propyl-4-ethoxy-alpha-naphthamidine.
18. N,N-di-isopropyl-4-ethoxy-alpha-naphthamidine.
- 45 19. N,N-di-n-butyl-4-ethoxy-alpha-naphthamidine.
20. N,N-di-isobutyl-4-ethoxy-alpha-naphthamidine.
21. N,N-di-sec-butyl-4-ethoxy-alpha-naphthamidine.
22. N,N-diethyl-4-n-butoxy-alpha-naphthamidine.
23. N,N-di-n-butyl-4-n-butoxy-alpha-naphthamidine.
- 55 24. N,N-di-sec-butyl-4-n-butoxy-alpha-naphthamidine.

The compounds according to the present invention are conveniently prepared as described in our co-pending application Serial No. 700,366 above mentioned, by the reaction of a

halomagnesium dialkylamide of the formula $RR'NMGY$ (in which Y is a halogen atom) upon a 4-alkoxy-alpha-naphthonitrile. The product initially formed is the halomagnesium derivative of the amidine. When the reaction mixture is hydrolyzed, as by iced ammonium chloride solution, the halomagnesium radical is replaced by hydrogen, liberating the amidine which can be separated by procedures described below and transformed to suitable salts for easier manipulation and greater stability.

The nitriles employed in the preferred synthesis are readily obtained by the following series of reactions:

Methods for the preparation of the substituted amidines according to the present invention are illustratively exemplified in the following examples which, however, are not intended to limit the scope of the invention:

Example 1.—N,N-di-n-propyl-4-methoxy-alpha-naphthamidine

To a solution of ethyl magnesium bromide in ether, prepared from 2.5 g. of magnesium and 10.8 g. of ethyl bromide was added gradually 10.1 g. of di-n-propyl amine and the solution was refluxed thirty minutes after the addition had been completed. There was then added slowly 9 g. of 4-methoxy-alpha-naphthonitrile dissolved in ether and the whole was refluxed four hours. The reaction mixture was poured into iced ammonium chloride solution and the ethereal layer was separated. The aqueous layer was basified further with aqueous alkali, extracted with ether and the extract combined with the previous ethereal layer. These ethereal layers were washed with dilute sodium hydroxide solution, filtered from a little precipitated magnesium hydroxide and dried over potassium carbonate. The dry ethereal solution was evaporated on the steam bath, finally in vacuo to remove traces of secondary amine. The residue which was a brownish oil weighing 12.5 g., was dissolved in absolute ethanol containing two g. of hydrogen chloride and ether was added to induce crystallization. The hydrochloride, after recrystallization from ethanol-ether mixtures, melted at about 226° C. with decomposition.

Example 2.—N,N-di-isopropyl-4-methoxy-alpha-naphthamidine

A Grignard reagent was prepared from 5 g. of magnesium and 21.6 g. of ethyl bromide and was reacted with 21.8 g. of di-isopropylamine, the solution being refluxed thirty minutes after addition was complete. Ten g. of 4-methoxy-alpha-naphthonitrile was added gradually and the reaction mixture was refluxed four hours. Hydrolysis was performed with iced ammonium chloride solution. The ethereal layer was first extracted with N-hydrochloric acid and the acid

solution was basified with alkali. The amidine base was taken into ether, dried over potassium carbonate and the dry solution was evaporated in vacuo (on the steam bath). The residue, which weighed about 14 g. (calculated 15.5 g.) solidified on standing. It was recrystallized from ether-hexane mixture and transformed to the hydrochloride which melts at 241° C. The hydrochloride can be crystallized from ethanol-ether mixtures.

Example 3.—N,N-di-n-butyl-4-methoxy-alpha-naphthamidine

One-fifth mole (26 g.) of di-n-butylamine was added gradually to a solution of ethylmagnesium bromide prepared from 5 g. of magnesium and 22 g. of ethyl bromide. After addition of secondary amine was complete the solution was refluxed thirty minutes and a solution of 18.3 g. (0.1 mole) of 4-methoxy-alpha-naphthonitrile in 100 cc. of absolute ether was admitted slowly. When all the nitrile was in, the solution was refluxed three hours and poured into iced ammonium chloride solution. A magnesium derivative of the amidine precipitated as a solid at this point and was filtered off, thereby effecting separation from secondary amine. On treatment with alkali and extraction with ether the amidine passed into the ethereal layer which was dried over potassium carbonate and evaporated. The amidine base was a light yellow oil weighing 26 g. (83.5% yield). The oil was dissolved in 50 cc. of absolute ethanol, and 10 g. of 35% ethanolic hydrogen chloride (wt./wt.) was added. The solution was diluted with absolute ether to the point of incipient turbidity, whereupon the hydrochloride separated on scratching. This salt melted at 230° (dec.), when first obtained and subsequent recrystallizations from ethanol-ether mixtures did not raise the melting point.

Similarly, bromomagnesium di-n-butylamide reacted with 4-ethoxy- and 4-n-butoxy-alpha-naphthonitriles to yield N,N-di-n-butyl-4-ethoxy- and N,N-di-n-butyl-4-n-butoxy-alpha-naphthamidines whose hydrochlorides melt at 234-5° C. and 219° C. respectively.

Example 4.—N,N-di-isobutyl-4-methoxy-alpha-naphthamidine

A solution of ethyl magnesium bromide was prepared from 2.4 g. of magnesium and 10.8 g. of ethyl bromide. Fourteen g. of di-isobutylamine was added gradually and the solution was refluxed one-half hour. Nine g. of 4-methoxy-alpha-naphthonitrile was added dissolved in a 50-50 mixture of ether and benzene and the reaction mixture was refluxed three hours. After hydrolysis, the amidine base was separated by the method of Example 2 and transformed to the hydrochloride which melted at 237° C. after recrystallization from ethanol-ether mixture.

Example 5.—N,N-di-sec-butyl-4-methoxy-alpha-naphthamidine

A solution of bromomagnesium di-sec-butylamide was prepared by the addition of 14 g. of di-sec-butylamine to a solution of ethyl magnesium bromide formed from 2.5 g. of magnesium and 10.8 g. of ethyl bromide. After the usual thirty minutes refluxing 9 g. of 4-methoxy-alpha-naphthonitrile dissolved in benzene was added and refluxing was continued for 4½ hours. Hydrolysis and separation of amidine base was as described in Example 2. The base was transformed to the hydrochloride which melted initially at 237° C.

and, after recrystallization from ethanol-ether mixture, melted at 241° C. (dec.).

Bromomagnesium di-sec-butylamide was also reacted with 4-n-butoxy-alpha-naphthonitrile to give N,N-di-sec-butyl-4-n-butoxy-alpha-naphthamidine.

Example 6.—N,N-di-iso-amyl-4-methoxy-alpha-naphthamidine

Bromomagnesium di-iso-amyl amide, prepared by the procedures of the previous examples, was reacted with 4-methoxy-alpha-naphthonitrile to form N,N-di-iso-amyl-4-methoxy-alpha-naphthamidine. Since the secondary amine in this case is relatively involatile the ethereal solution of the amidine base was evaporated at 120° C. in vacuo instead of on a steam bath. The residual base weighed 15.5 g. (91%) and formed a hydrochloride that melted initially at 207° and at 208° after recrystallization from ethanol-ether mixture. The base must therefore have been substantially pure as isolated, although not crystalline.

Similarly, N,N-di-n-amyl-4-methoxy-alpha-naphthamidine (M. P. of hydrochloride, 209° C.) was obtained from 4-methoxy-alpha-naphthonitrile and bromomagnesium di-n-amyl amide.

By the application of the methods above described N-n-propyl-N-n-amyl-4-methoxy-alpha-naphthamidine, and N-methyl-N-n-nonyl-4-methoxy-alpha-naphthamidine were also prepared from the appropriate bromomagnesium di-alkylamides and 4-alkoxy-alpha-naphthonitriles.

We claim:

1. Substituted amidines of the type represented by the formula

in which R and R' are alkyl groups containing together from four to ten carbon atoms, and R'' is a lower alkyl group containing one to four carbon atoms, and the water soluble salts of these amidines with non-toxic acids.

2. Substituted amidines of the type represented by the formula

and the water soluble salts of these amidines with non-toxic acids.

3. Substituted amidines of the type represented by the formula

and the water soluble salts of these amidines with non-toxic acids.

4. N,N-di-n-butyl-4-methoxy-alpha-naphthamidine and its water soluble salts with non-toxic acids.

5. N,N-di-n-butyl-4-methoxy-alpha-naphthamidine hydrochloride.

6. N,N-di-sec-butyl-4-methoxy-alpha-naphthamidine and its water soluble salts with non-toxic acids.

7. N,N-di-sec-butyl-4-methoxy-alpha-naphthamidine hydrochloride.

8. N,N-di-n-butyl-4-ethoxy-alpha-naphthamidine and its water soluble salts with non-toxic acids.

9. N,N-di-n-butyl-4-ethoxy-alpha-naphthamidine hydrochloride.

RICHARD BALTZLY.
